KITCHEN IMPLEMENT

Harry Hertzberg, New York, N. Y., assignor to
 Hertzberg Patents, Inc., New York, N. Y., a corporation of New York

Application September 5, 1936, Serial No. 99,553

8 Claims. (Cl. 15—105)

This invention relates to mops and more particularly to that type of mop used for cleaning pots and pans in household use.

It is an object of the present invention to provide an implement which permits not only the mopping and cleaning of kitchen ware but also the removal of baked on particles by scrubbing and scraping the surface to be cleaned.

It is another object to provide an implement of this kind which is very simple in construction and consists of a small number of parts and therefore may be sold at a very small price.

It is a further object to provide means on a mop of this type for holding a wad of abrasive or spongy cleaning material and for permitting renewal or exchange of such material.

Other objects and advantages of the invention will be apparent from the description thereof taken in connection with the accompanying drawing in which—

Figure 1 is a side view of a mop embodying the present invention and partly in section on the line 1—1 of Fig. 2.

Figure 2 is a side view of the device showing it in use for removing substance from a surface and for cleaning it simultaneously.

Fig. 3 is a side view of the device showing its application for rubbing hard baked on substances from a surface.

Fig. 4 is a sectional view taken on the line 4—4 of Fig. 1.

Referring to the drawing, 10 represents mopping material, consisting preferably of cotton cords, and 11 is a wad of scrubbing material such as steel wool or sponge rubber. The cotton cords 10 and the scrubbing material 11 are held together by ring shaped loops 12a and 12b, respectively, formed by a single metal wire 12 so that the scrubbing material 11 is placed in front of the mopping material and covers the wire ring 12a enclosing it completely in the conical member. The wire ends are twisted to form a stem or tang 13.

A scraper or squeegee plate 14 is mounted on the tang 13. This scraper is preferably square shaped as shown in Fig. 4 and is provided at its front side with a conical extension or funnel 15 which covers the loop 12a and partly the wad of cleaning material 11. The plate 14 with its funnel 15 may be made of different material to suit the cleaning operations to be performed for light cleaning, such as semi-hard rubber. Wad 11 may be made of sponge rubber for certain purposes and for more intensive cleaning and scrubbing the plate and funnel members may be made of metal and the wad 11 may be removed by pushing it out of loop

12b (Fig. 1) and be replaced by one of steel wool or other suitable cleaning material.

The tang 13 is embedded in an axial bore in the end of a wooden handle 16 whereby all the parts of the mop are securely held in their relative positions.

In Fig. 2 the improved mop is shown as being used for light work in which case the squeegee or pliable rubber plate 14 pushes off soft substances while the sponge rubber pad 11 presses through the mop cords, which have opened up at the bottom as they are pushed back under funnel 15, and touches the surface to be cleaned.

When heavier or harder work is to be accomplished, a scraper 14 of metal may be substituted and pushed or scraped along the surface to remove hard substances or baked on substances. For such work also the member 11 may be formed of steel wool and may engage the surface directly as shown in Fig. 3 by pushing back the cotton cords, and thus rub off and polish spots on the surface.

The member 11 when soiled or worn may easily be renewed by pushing it out of the loop 12a and pushing a new one through the same.

The improved mop has been shown only in its preferred form and it should be understood that changes in details may be made without departing from the principle of the invention and therefore I desire to be limited only by the state of the prior art and the appended claims.

I claim:

1. A mop including a handle, a looped wire having end portions fixed within said handle, mop threads held within the looped part of said wire and having their ends depending cup shaped from said handle and a wad of soft, resilient cleaning material also held by said wire so that said cleaning material is surrounded by said cup shaped mop threads and a resilient tubular member surrounding the wire loop and a portion of the mop threads held thereby and connected to said handle by means of said wire.

2. A mop including a handle, mop threads at one end of said handle, a wad of soft, resilient cleaning material, a looped wire surrounding said cleaning material and said mop threads and having a stem held axially in said handle and a scraper plate on said stem between said threads and said handle.

3. A mop including a handle, a bunch of mop threads, a looped wire surrounding said threads and having a twisted tang within said handle, a flat scraper plate between said threads and said handle, and a wad of soft, resilient cleaning mate-

- rial held by said wire adjacent to said threads on the side opposite to said handle.
4. A mop comprising a handle, a polygonal scraper plate lying flat against one end-face of said handle, a hollow conical portion integral with said plate concentric therewith and flaring outward therefrom, and mop material held within said conical portion by means of a looped wire surrounding said mop material and having a stem 10 passing through said plate into said handle.
5. A mop comprising an elongated handle, a polygonal scraper plate arranged concentrically with and perpendicularly to the handle axis, mop threads and a wad of soft resilient cleaning material held on said plate on the side opposite to said handle by means of a looped wire surrounding said mop threads and said cleaning material and having a stem passing through said plate into said handle.
- 15 6. A mop comprising an elongated handle, a cup shaped member in axial alignment with said handle and having the bottom part of the cup adjacent to the handle, mop threads within said
- cup, a looped wire encircling said threads, a wad of soft, resilient cleaning material held by the said wire adjacent to the said mop threads and a tang formed by said wire passing through said cup into said handle. 5
7. A mop comprising a substantially cylindrical handle, a cup shaped member in axial alignment with said handle and having the bottom part of the cup adjacent to the handle, mop threads within said cup, a looped wire encircling said threads, a wad of soft resilient cleaning material held by a second loop of the said wire adjacent to said mop threads and a tang formed by said wire passing through said cup into said handle. 10
8. A mop including a handle, mopping material at one end of said handle, a wad of cleaning material in front of said mopping material, a rubber scraper behind said mopping material and a wire member extending through said mopping material and scraper for securing same to the handle, said wire member having a loop portion for removably holding the wad of cleaning material. 15
